UNITED STATES PATENT OFFICE.

HERBERT L. AMENT, OF LOS ANGELES, CALIFORNIA.

HAND PRINTING-PRESS.

1,175,497.

Specification of Letters Patent. Patented Mar. 14, 1916.

Application filed June 2, 1910. Serial No. 564,586.

To all whom it may concern:

Be it known that I, HERBERT L. AMENT, a citizen of the United States, residing at Los Angeles, in the county of Los Angeles and State of California, have invented new and useful Improvements in Hand Printing-Presses, of which the following is a specification, reference being had to the accompanying drawings, forming a part 10 thereof.

The purpose of this invention is to provide an improved apparatus of the nature of a hand printing press, particularly adapted for printing by means of an inked 15 ribbon impressed by the type upon the paper.

It consists of the elements and features of construction shown and described as indicated in the claims.

20 In the drawings:—Figure 1 is a plan view of a printing press embodying this invention with the platen roll partly broken away. Fig. 2 is a partly sectional side elevation of the same, one side of the fixed 25 frame being broken away, and section being made in a vertical plane transverse to the axis of the platen roll through the latter and through certain other parts at the line 2—2 on Fig. 4. Fig. 3 is a transaxial section of a modified form of a platen roll having a special form of covering. Fig. 4 is a section at the line 4—4 on Fig. 2. Fig. 5 is a plan view of a chase which forms a 30 part of the printing machine. Figs. 6, 7 and 8 are side elevations of three forms of 35 slugs or fillers employed in the chase. Fig. 9 is a section at the line 9—9 on Fig. 2.

The structure shown in the drawings 40 comprises a fixed frame, 1, in which there is mounted for reciprocation a chase and ribbon carrier, 2, a platen roll, 3, and a chase-supporting roll, 4. The carrier, 2, is a frame having at opposite sides at the top, flanges, 5, 5, which are lodged for sliding 45 upon flanges, 6, 6, of the frame, 1, the said carrier being by this means suspended on the frame, 1, underneath the platen roll, 3, for carrying the chase back and forth under said roll. The chase or type-con- 50 tainer, 7, is a shallow box or pan which is lodged upon and supported by the longitudinal upper side bars of the carrier, 2, between which bars it is suspended and fits snugly (see Fig. 4). The roll 4 is positioned in the frame, 1, so that the bottom of

the chase may be lodged and ride upon said roll in the reciprocation of the carrier, 2, said roll, 4, having its axis in the same vertical plane as the platen roll, 3, so that the pressure of the two rolls,—the former below and the latter above the chase and type therein,—are directly opposed to each other in the line of the type between them. In the carrier, 2, upon lower longitudinal bars, 8, 8, of said carrier, there are mounted the 60 ribbon-carrying drums, 9, 9, with their axes transverse to the path of reciprocation of the carrier, having the ribbon, 10, wound at one end upon each roll and immediately passing about the guide rolls, 11, 11, 65 mounted in the carrier at the upper opposite end corners with their upper sides a little below the plane of the face of the type, 12, set in the chase; so that the ribbon extending from guide roll to guide roll 70 above the chase droops off a little from the top of the type to the guide rolls, as is necessary in order that the platen roll position for pressing upon the top of the type or upon the ribbon thereabove does not press 75 the ribbon upon the guide roll, 11. The two drums, 9, 9, are connected by drive chain, 13, passing about pulleys, 9^a, on the drums for communicating rotation of one to the other, and causing each to act as a 80 brake on the other, preventing excessive unwinding of the ribbon by momentum of the drum from which it is being unwound. It will be understood that the chain will slip on the pulleys to accommodate the variation 85 in the give-and-take of the two drums due to the difference in amount of ribbon wound on them respectively varying in their effective diameter. Upon one end of the axle of one of the drums and upon the 90 opposite end of the axle of the other, there is fast a gear pinion, 14, preferably of ratchet type, so as to be adapted to be rotated in one direction only, and upon the fixed frame, 1, at one end at one side and 95 the opposite end at the other side, there is mounted a rack bar, 15, having its rack teeth, 15^a, also of ratchet type for engaging the pinion, 14, when by the travel of the carrier the pinion encounters the rack 100 teeth.

Each rack bar is located and provided with the rack teeth in position to be encountered by the pinion, 14, of the drum at the remote end of the carrier from that end 110

of the frame upon which the rack bar is mounted when the carrier is moved past the platen roll, 3, so far as to have carried the entire body of type set in the chase past the roll and out of contact therewith, and to a point at which the ribbon is not pressed against the platen roll; and during the remainder of the stroke or travel of the carrier in the same direction in which it has moved to thus carry the type past the platen roll, the pinion, 14, on the shaft of one of the drums being engaged with the rack teeth causes that drum to be rotated for winding the ribbon thereonto and off the other drum to an extent corresponding to the length of the rack, which is designed to be sufficient to propel the ribbon far enough to deliver the paper over the drum onto which the ribbon is being wound. It will be observed that the structure described causes the ribbon to be thus propelled in opposite directions at the opposite limits of the stroke of the carrier, and that if the two racks were positioned for engagement with the respective pinions at the same distance from the end of the structure so as to give equal rotation of the two drums in the respective strokes the ribbon will be thus propelled back and forth equal distances and would present the same two portions of its area alternately above the chase for pressure of the platen roll upon it in printing. In order to prevent this result which would exhaust the ink from the particular spots in which the type would press upon it, one of the racks is positioned for encounter with the pinion a little earlier in the stroke than the other, with the effect of giving the drum actuated by this rack a little longer period of actuation than the other drum receives from the other rack; for it should be understood that in practice the rotation of the drums may continue longer than the actual engagement of the rack and pinion; that is after the pinion has traveled the length of the rack teeth by reason of the momentum of the drums derived from the first encounter of the pinion and rack, so that the earlier encounter practically gives the longer action whether the actual length of the racks may be the same or not.

Mounted upon the fixed frame, 1, extending from side to side thereof, at each side of the platen roll, 3, are flat transverse bars, 20, 20, extended at their ends to form foot pieces, 20^a, for securing them to the side standards of the frame, 1, said flat bars being mounted with their width inclined at an angle of about forty-five degrees. Each 55 of said bars has midway between its ends a bracket arm, 21, extending off at right angles to its length in the inclined plane of its width. The bracket, 21, has a longitudinal slot, 21^a, and at the upper outer end an offset lug, 21^b. On the bracket there is mount-

ed for engaging in the slot and sliding on the bracket a T-fitting, 22, whose stem, 22^a, is threaded and extends through the slot receiving below the bracket a thumb nut, 24, for clamping said fitting tightly upon the bracket at any position in the length of the slot at which the fitting may be set. A feed screw, 25, journaled in the offset lug, 21^b, takes through the fitting, 22, for feeding it up and down on the inclined bracket. A 75 rod, 26, is mounted in the upper end of the T-fitting, 22, extending transversely of the machine,—that is, parallel with the platen roll axis,—and on the two end portions of the bar,—that is, upon opposite sides of the 80 T-fitting,—there are mounted paper-supports, 27, 27, which extend in an inclined direction at an angle of about forty-five degrees, the greater portion of the extent being upward and back from the pivot of 85 the paper-support on the rod, 26, the shorter portion extending down from the rod under the platen roll, said portion consisting only of an arm, 27^a, at the lower end of which there is mounted a roll, 27^b, which bears upwardly against the under side of the platen roll for holding the paper thereagainst to cause the individual sheets to be fed by the platen roll down onto the ribbon above the chase as the platen roll is revolved and the chase is propelled under the platen roll. The two supports, 27, 27, are adjustable on the rod, 26, to adapt them to different widths of paper, each support having at the outer side a flange, 27^c, which serves as a gage for the 100 paper, and the supports being preferably adjustable so that the paper may pass freely but without appreciable play between the two opposite gage flanges. To facilitate this adjustment and hold the supports in 105 adjusted position on the rod, the latter is threaded and provided on each end portion with nuts, 24^a, 24^b, respectively, outside and inside the lug, 27^a, which forms the outer pivotal bearing of the support 27. There is 110 formed back of the roll, 27^b, an upwardly extending stop finger, 27^e, whose under edge stands at an acute angle to the upper edge of the arm, 27^a, so that a quantity of sheets of paper lodged on the support with their 115 lower edges stopped by the finger are caused to present their upper edges slightly separated, each sheet being pushed back a little above the sheet below it so that the top sheet 120 can be readily grasped to separate it from the pile.

For rotating the platen roll, a crank handle, 30, may be attached to the squared end, 3^b, of the shaft, 3^a, of said platen roll, or to the squared end, 4^b, of the shaft, 4^a, of the roll, 4, the movement in the latter case being communicated to the platen roll through the chase, which is engaged between the roll 4 and platen roll. The diameter of the platen roll is preferably to be such that its cir- 130

cumference will be greater than the dimension in the direction of travel of the largest sheet for which the apparatus is designed, such circumference being therefore greater than the full length of the chase, which would be the maximum length of the printing area and would approximate the maximum dimension in that direction of the sheet to be printed. Each of the paper supports, 27, being supplied with a quantity of paper represented at 40, the carrier, 2, being at one limit of its path of travel or stroke, the operator will lift the top sheet from the pile on the paper support at that side, and lodging its lower edge upon the upper side of the stop fingers, 27^c, which slope at a very acute angle to the proximate under surface of the platen, the sheet will slide down on said finger and onto the rolls, 27^b, and upon rotation of the platen roll in the proper direction, the sheet will be drawn between the platen roll and the ribbon and pressed upon the face of the type in the chase while the carrier, 2, makes its stroke under the platen roll to the point at which the pinion, 14, encounters the rack bar, 15. At this stage, the platen roll has passed off the face of the type and the ribbon is free from the grasp of the platen roll and type, and being now by the engagement of the pinion with the rack propelled over the chase in the direction opposite to that in which the carrier is traveling, the sheet of paper lying upon the ribbon is propelled back past and out from under the platen roll and off the chase and lodges in a basket, 41, which is provided for that purpose mounted underneath the path of the carrier. For stopping the paper and preventing it from being shot over the basket, there is provided a wire guard, 42, upstanding at the outer side of the basket, such guard being mounted upon the fixed frame, 1. The operator will now lift a sheet from the pile on the support at the side of the platen roll to which the carrier has moved, and depositing it in the same manner as before upon the upper side of the fingers, 27^c, and reversing the rotation of the platen roll, will cause the printing operation to be repeated upon the second sheet, which will be deposited in a basket 41, at the other end of the frame. An impression will thus be made at each stroke of the ribbon-and-chase carrier in each direction.

The construction of the chase and its furniture or fillers other than type is contrived for the purpose of equalizing the movement of travel of the chase with the peripheral movement of the platen roll, and producing substantially or approximately equal impression upon all lines of type, whether full-length or fractional. For this purpose, there are provided for interposition between the consecutive lines of type to properly space them, reglets or fillers, 50, which are

cut away between their ends on the upper side to reduce the height adequately below the face of the type, the end portions, 50^a, being left substantially type-high so that the platen roll will bear upon said ends and be prevented from settling between the lines of type, which would cause the impression to be marred by being intensified at the edges of the type. The pressure of the platen roll is designed to be such that when the lines of type are substantially full, that pressure being distributed thus over the full line is not too great but adequate only to produce the proper impression for printing, and the variation in this respect from a half line to a full line may generally be regarded negligible; that is, the difference in the impression upon a half line and a full line, except sometimes in the case of an exceptionally inked ribbon, is not more than can be permitted without marring the appearance of the sheet; and in all such full or approximately full lines, 12, the chase is filled out to the margin at each end of the line with ordinary slugs, 51, whose height is that of the middle portion of the reglets, 50;—that is, sufficiently below type-height to prevent any impression being made. But in case of lines which are less than half full, the end portions are filled with reglets, 52, having one end portion of full type-height and the remainder of the length reduced, thus affording support for the platen roll at the ends as it is supported by the fillers, 50, between the lines. It will be understood that “furniture” for filling the chase beyond the range of the composition at either end or at any extended intermediate portions which are without composition, will be provided in the form substantially of the reglets, 50, but of any width or widths to facilitate rapid assembling, and that any customary means may be provided for locking the assembled type slugs and furniture in the chase. For the purposes for which such a press is designed, very slight locking is sufficient, and usually it will be preferred simply to fill the chase snugly with furniture, dispensing with any special clamping means.

For reducing to a minimum the variation in the appearance of the printed lines which might be caused by the varying pressure to which the individual longer and shorter lines are subjected, the platen roll is preferably provided with a face for bearing upon the ribbon formed of material having only very slightly yielding character, and yet not so hard as to fail to impress all the type faces and every part of such faces; when, as is likely to be the case, some portion of such faces may be slightly more raised than the others. For this purpose the best material, according to my experience, is firm-fibered paper applied in several laminae or layers about the roll, wound quite

5 tightly thereon, the slight amount of air which notwithstanding tight winding is retained between the several laminæ, being sufficient to afford all necessary yielding-
ness, and operating to prevent the ribbon or
the outer layer of the paper being cut by
the type; that is rendering it unnecessary
10 to apply for producing a good impression
from the type any amount of pressure which
would operate to cut the ribbon or paper.

10 The employment of a plurality of layers of
paper affords in addition to the advantage
of the slight air cushion which is formed
between the layers, the further advantage
15 that the outer layer if at any time showing
indentations and roughness from the repeated
action of the type can be stripped off
and expose a new surface free from such
irregularity with a minimum interruption
20 of the printing operation. Such a construction
is shown in Fig. 3, the paper laminae
being indicated by reference character 60.

20 The platen roll shaft, 3^a, is preferably
journaled in boxes 58, 58, mounted for slid-
ing vertically in the frame 1, and for ad-
justing them to cause the platen roll to make
proper contact with proper pressure upon
30 the paper above the inking ribbon, a threaded
stem, 53, is mounted in the frame, 1, and
stopped against vertical movement therein
(except as hereinafter mentioned) by means
of a collar, 54, pinned on said stem and
engaged in a slot, 1^b, in the frame, 1, the
lower threaded end of the stem being
35 screwed into the upper end of the box and
the upper end of the stem having a hand
wheel for rotating it. Vertical play is pref-
erably allowed by making the collar, 54, a
little less in thickness or vertical dimension
40 than the vertical dimension of the slot, 1^b,
above illustrated.

40 The chase or type container, 7, is pref-
erably made of sheet metal or other sheet
material sufficiently stiff to retain its form
45 when loaded with the type, but having the
bottom at least somewhat flexible, so that
as each line of type supported upon the bot-
tom passes the vertical plane of pressure,
that is the vertical plane containing the axes
50 of the platen roll, 3, and the chase support-
ing roll, 4, any inequalities or buckling in
the bottom of the chase or type pan may
be straightened out without materially
varying the pressure on the face of the type
55 at different parts of the line; and also so
that inequalities or buckling in the bottom
elsewhere than immediately at the line un-
der pressure will not occasion, by the re-
sistance to straightening, inequalities of
60 pressure at the line which is being printed.
This feature of construction consisting in
the employment of a sheet metal pan for
holding the type obviates a serious difficulty
which is involved in the use of a rigid bot-
tom plate or support for a chase or type bed

or a chase or pan having a rigid bottom,
that difficulty being that such a rigid sup-
port for the type must be planed down to
absolute accuracy of surface in order to
70 avoid inequality in pressure and unequal in-
tensity of printing, which when such a rigid
base is used, can only be obviated by the ex-
pedient of backing up the type by the in-
sersion of slips of paper or other backing.
When the flexibly bottomed chase or type
75 pan is employed, made of sheet metal whose
thickness by reason of the method in which
the sheet metal is produced by rolling is as
nearly absolutely uniform as it is possible
to obtain by any means, the uniformity of
80 the type which is sufficiently reliable, in-
sures uniformity of pressure except as to
the slight differences due to the buckling
which are negligible on account of the flexi-
bility of the sheet metal. Preferably in
85 view of the employment of the compara-
tively light sheet metal pan for holding the
type, there is provided a supplemental seat
or holder for this type pan or chase, rep-
resented at 56, which is also of sheet metal,
90 and similarly flexible. This holder is pro-
vided at its lateral edges with flanges, 56^a,
by which it is lodged upon a shoulder
95 formed by rabbeting the inner upper longi-
tudinal corners of the upper side bars of the
carrier, 2.

To arrest the travel of the carrier at the
limits of its stroke in each direction, it may
be provided with bumpers, 57, at each end,
which collide with the roll, 4, at the end of
100 the strokes respectively.

When the ribbon has been wound entirely
from one drum onto the other, it may be re-
wound on the first drum by two or three
quick strokes of the carrier at the position
105 of which the pinion, 14, of the drum onto
which it is to be re-wound, is engaged with
its rack, 15^a; the momentum of the drums
being sufficient to wind the ribbon rapidly
and making it unimportant to provide auto-
matic means for reversing the winding.

To insure the ribbon running true from
guide to guide over the chase, I provide on
the guide rods, 11, sloping shoulders, 11^a, at
the paths of the lateral edges of the ribbon
115 which cause the latter to slip inward to
proper position while being propelled over
the chase if it has been by any cause dis-
placed laterally so as to lap on either of
the inclined shoulders.

I claim:

1. In a printing machine, in combination
with a chase mounted for reciprocation, an
inking ribbon extending over the chase for
supporting the sheet to be printed, two
125 drums on which the opposite ends of the
ribbon are wound, both mounted for recipro-
cation with the chase and with their axes
transverse to the path of reciprocation, and
means for discharging the sheet comprising
130

means for rotating the drums at the finishing portion of each stroke of the chase, such means being adapted to move the ribbon by a substantial proportion of the length of the 5 type form.

2. In a printing machine in combination with a chase mounted for reciprocation; an inking ribbon and rotatably mounted drums on which it is wound also mounted for reciprocation, means connecting the drums for simultaneous rotation, and means for actuating one of the drums for such rotation at the finishing portion of each stroke of the chase.

15 3. In a printing machine in combination with a chase mounted for reciprocation, an inking ribbon and two rotatably mounted drums on which it is wound at its opposite ends also mounted for reciprocation with 20 the chase; means connecting the two drums for simultaneous rotation, and means for actuating the drums alternately at the finishing portion of the respective opposite strokes of the chase.

25 4. In a printing machine in combination with a chase mounted for reciprocation, an inking ribbon and rotatably mounted drums on which it is wound mounted for reciprocation with the chase, pinions on the drum 30 shafts and racks in fixed positions along the path of reciprocation of the chase for engaging the pinions respectively toward the limits of the opposite strokes of the chase to rotate the drums.

35 5. In a printing machine in combination with a chase mounted for reciprocation, an inking ribbon and rotatably mounted drums on which it is wound mounted for reciprocation with the chase, means connecting the 40 two drums for simultaneous rotation, a pinion on the shaft of each drum and a rack for engaging each pinion fixed in position along the path of reciprocation of the pinion toward the limit of the stroke of the 45 chase to actuate the drums respectively.

6. In a printing machine in combination with a platen roll, a carrier mounted for reciprocation past the roll, a chase and contents and an inking ribbon mounted on the 50 carrier, rotatably mounted drums on the carrier on which the inking ribbon is wound, the chase and contents comprising substantially type-high marginal portions for frictional engagement of the platen roll to 55 equalize the peripheral movement of the roll with the movement of travel of the chase, and means for rotating the drums independently of the platen roll at the finishing portion of each stroke of the chase to propel the 60 ribbon over the chase.

7. In a printing machine in combination with a platen roll, a carrier mounted for reciprocation past the roll, a chase and contents and an inking ribbon both mounted on 65 the carrier, rotatably mounted drums on the

carrier on which the inking ribbon is wound, means for reciprocating the carrier, the chase and contents comprising substantially type-high marginal portions for frictional engagement of the platen roll to equalize the 70 peripheral movement of the roll with the movement of travel of the chase, the path of the ribbon over the chase at the end portions thereof being lower than the lower side of the platen roll, and means for rotating the 75 drums independently of the platen roll at the finishing portion of each stroke of the chase to propel the ribbon over the chase.

8. In combination with a platen roll, a carrier mounted for reciprocation past the 80 roll, a chase mounted on the carrier; an inking ribbon extending over the chase; rotatably mounted drums on which it is mounted at its opposite ends; means by which the roll engages the chase for equalizing the peripheral movement of the roll with the movement of travel of the carrier; means connecting the two drums for simultaneous 85 rotation; a pinion on the shaft of each drum and a rack for engaging each pinion mounted in fixed position along the path of the pinion toward the limit of the stroke of the carrier, for rotating the drums to propel the ribbon in the opposite direction of such stroke.

9. In a printing machine in combination with a platen roll, a printing member mounted for reciprocation tangent to the roll; a paper-support pivoted in inclined position at one side of the platen roll; paper-pressing rolls on the lower end of said support positioned for bearing upward against the under side of the platen roll, the paper-support having guard fingers located back of said roll, projecting up from 105 the paper-support at an acute angle therewith.

10. In combination with a platen roll, a carrier mounted for reciprocation past the platen roll; a chase on the carrier with sides 110 parallel to the path of said reciprocation; a platen-opposing roll at the opposite side of the chase from the platen roll, the chase and contents comprising substantially type-high marginal portions for bearing on the platen roll interrupted at the longer lines of type.

11. In a printing machine in combination with a platen roll and a platen opposing roll, a frame in which they are both journaled, a chase and a carrier for the same 115 mounted for reciprocation of the chase between the platen roll and the platen opposing roll, the chase consisting of a bottomed receptacle for the type, the bottom being of flexible sheet material.

12. In a printing machine in combination with a chase mounted for reciprocation, an inking ribbon and rotatably mounted drums on which it is wound, means for rotating the drums at the finishing portion of each stroke 120

of the chase, pulleys on the drum shafts and an endless band encompassing them for braking.

13. In a printing machine in combination with a chase mounted for reciprocation, an inking ribbon, and rotatably mounted drums on which its opposite ends are wound; means for rotating the drums at the finishing portion of each stroke of the chase, pulleys on the drum shafts, and an endless chain encompassing them.

14. In a printing machine, in combination with a frame, a chase and contents mounted for reciprocation therein, a platen roll journaled for rotation tangent to the path of reciprocation of the chase; feed rollers mounted in contact with said platen roll at both sides of its axis and near the path of the chase; magazine paper holders adjacent to said feed rollers; means by which the platen roll engages the chase for equalizing the peripheral movement of the roll with the

travel of said chase; means for rotating the platen roll and means for automatically discharging printed sheets from the chase during the finishing portion of each stroke of its reciprocation.

15. In a printing machine in combination with a platen roll and a platen-opposing roll; a frame in which they are both journaled; a chase and contents mounted for reciprocation between the platen roll and the platen-opposing roll, the bottom of said chase being of flexible sheet material and the contents comprising type and fillers set in lines parallel to the axes of the rolls.

In witness whereof, I have hereunto set my hand at Chicago, Illinois, this 23rd day of May, 1910.

HERBERT L. AMENT.
